William H. Plunkett

By his attorney

Henry Moulton

UNITED STATES PATENT OFFICE.

WILLIAM H. PLUNKETT, OF RICHMOND HILL, NEW YORK, ASSIGNOR TO BERNICE B. PLUNKETT, OF RICHMOND HILL, NEW YORK.

SPARK-PLUG.

1,291,122.

Specification of Letters Patent. Patented Jan. 14, 1919.

Application filed August 31, 1918. Serial No. 252,164.

To all whom it may concern:

Be it known that I, WILLIAM H. PLUNKETT, a citizen of the United States, residing at Richmond Hill, in the county of 5 Queens and State of New York, have invented certain new and useful Improvements in Spark-Plugs, of which the following is a full, clear, and exact description.

This invention relates to spark plugs, and 10 has for its general object the provision of a device which combines the functions of an energizer and a spark plug.

As is well known, an energizer is a device 15 for introducing a spark gap into an ignition circuit at a point other than the sparking contacts for the purpose of increasing the size of the spark and also for preventing short circuits either at the sparking contacts, due to an accumulation of carbon, or short 20 circuits through the porcelain insulator. These energizers have been usually placed at a point adjacent to the spark plug and it is the primary purpose of this invention to combine the energizing function with the 25 spark plug, so that an integral device is obtained which will have both functions.

It is also the object of the invention to 30 provide a device or spark plug of this character, which is of simple construction, which may be readily assembled, and which when assembled may be placed in the cylinder of the internal combustion engine in the same way as any of the usual types of spark plugs at present used.

35 A further object of the invention is to provide an insulator which combines with the sparking contacts to prevent any accumulation of dirt or carbon at the contacts, which might cause a fouling of the plug.

40 Other objects of the invention will be apparent from the detailed description hereinafter to follow, when taken in conjunction with the accompanying drawing, and will be particularly pointed out in the appended 45 claims.

In the drawing, Figure 1 shows a view, 50 partially in section, of one type of spark plug constructed in accordance with the principles of the invention; and

Fig. 2 is a bottom plan thereof.

The outside shell or bushing 1 of the spark plug, which is of metal, as is the usual practice, is provided with a reduced end 2, which is threaded for the purpose of securing 55 the plug in place within the cylinder

head. This shell or bushing carries one of the sparking contacts, which is designated 3, which, in the form shown, consists of a rod of metal extending radially to the center of the opening within the reduced end portion 2 of the shell to the center thereof, where it is provided with an upturned end 4.

60 Mounted within the shell or bushing 1 is an insulator which, in the form shown, comprises three sections designated 5, 6 and 7. 65 The lowermost section 5 carries a centrally disposed electrode 8, which has a projecting lower end in alignment with the end 4 of the other electrode or contact. This section 7 of the insulator is provided with a beveled portion 9, which is separated from a similar beveled portion 10 of the shell or bushing 1 by a copper asbestos cushion or seat 11. The lowermost end of the section 7 is of reduced diameter, and surrounding the projecting 75 end of the electrode is a cup-shaped depression 12. The ends of the electrodes 8 and 3 are disposed within this cavity or depression. The reduced end portion of the section 7 is also provided with fins 13 which serve to dissipate or radiate the heat and thus prevent 80 excessive heating of the electrode. The upper end of the section 7 of the insulator is provided with a centrally disposed boss 14 and the end of the electrode 8 also projects 85 beyond this boss. Mounted above the section 7 is the intermediate section 6, which is preferably separated from the lower section by a layer 16 of mica, or other insulation. This section also carries a centrally disposed electrode 17 which is embedded therein in the usual manner. The section 6 is also provided with a centrally disposed cylindrical opening or cavity, the lower end of which fits over the cylindrical boss 14. The cavity is, 90 however, of greater depth than the boss to provide a chamber *a* in which are positioned the alining ends of the electrodes 8 and 17. These ends are preferably somewhat pointed to decrease the resistance of the spark gap, 100 which is formed between them. The intermediate section 6 is also provided with a centrally disposed cylindrical boss 19. The upper section 5 of the insulator is also provided with a centrally disposed cylindrical 105 cavity, the lower end of which fits over the boss 19 to provide a second chamber *b* similar to the chamber *a*. The section 5 carries an electrode 20 having its end projecting into the chamber *b* in alignment with the 110

end of the electrode 17, with the ends spaced sufficiently apart to provide a spark gap at this point. The electrode 20 projects through the upper end of the section 5 of 5 the insulator and carries the usual terminal 21 for connecting the wire for the ignition circuit (not shown) to the spark plug.

The section 5 of the insulator is provided with a shoulder 23, and a gasket 24 which is 10 threaded into the open upper end of the shell or bushing 1 is screwed down upon the shoulder to firmly clamp the three sections of the insulator within the shell or bushing. This gasket is provided with a hexagonal 15 flange 25 for screwing it into position and is preferably separated from the shoulder 23 by a copper asbestos cushion.

The method of assembling the plug is obvious from its construction, the sections 7 20 and 6 being first placed within the shell and finally the section 5, which is then clamped in position by the gasket 24. The layers 16 and 19' which separate the sections of the insulator also serve as spacers to determine 25 the length of spark gap formed by the electrodes within the chambers *a* and *b*, for since the electrodes are rigidly secured in the insulators it is evident that the thickness of the layers of insulation will determine the 30 length of the spark gap.

In use the three spark gaps must be simultaneously arced in order to close the circuit, which will cause a higher potential to be accumulated than if only one spark gap is 35 utilized. The result of this is that a spark of greater size is produced at the electrodes 3 and 12, which will be of greater sharpness and brilliancy, due to the high potential which is caused by the plurality of spark 40 gaps. In practice, it has been found that the size and strength of the spark at the sparking contacts is sufficient to keep the sparking contacts clean at all times without any danger of fouling. The sparking contacts are preferably arranged as shown, that 45 is, positioned within the cup-shaped depression in the end of the insulator, which will prevent the accumulation of oil upon the sparking contacts, since the cup serves as a 50 reflector for the spark.

In other words, since the spark is fired within the cup the flame from the spark will, when it strikes the walls of the cup, be deflected or reflected outwardly, which will 55 tend to carry with it any accumulation of oil which may gather adjacent to the sparking contacts and will therefore maintain these contacts clean.

Heating of the electrode is also prevented by the heat-dissipating or radiating fins 13.

While a plurality of spark gaps are shown other than at the sparking contacts it is evident that one of such spark gaps would be of value, although it is believed that it would not be as efficient as the plurality of spark gaps shown. It is intended, however, that such a construction will come within the 65 purview of this invention as set forth in the appended claims.

I claim:

1. In a spark plug for internal combustion engines, a plurality of insulator sections, an electrode in each section and a separator between adjacent sections to control the size of the spark gap between the 70 ends of the electrodes.

2. In a spark plug for internal combustion engines, a metallic shell, a plurality of insulator sections in said shell, an electrode carried by each insulator section, the ends of adjacent electrodes being placed to provide a spark gap and a separator between 80 two adjacent insulator sections to control the size of the spark gap.

3. In a spark plug for internal combustion engines, a metallic shell, a sectional insulator mounted in said shell each section having an electrode passing axially therethrough, said sections arranged in abutting relation, the ends of said electrodes being spaced apart to provide a plurality of spark 85 gaps.

4. In a spark plug for internal combustion engines, a metallic shell, a sectional insulator in said shell having axially arranged electrode sections passing axially therethrough, and means for clamping the sections of the insulator to the shell, said electrode sections being spaced apart to provide a spark gap between two sections of the 90 insulator.

5. In a spark plug for internal combustion engines, a metallic shell, an insulator comprising a plurality of abutting sections mounted within said shell, said sections having a plug and socket connection, said sockets being of greater depth than said plugs to 100 provide cavities, means for clamping the sections of the insulator together and to the shell, an electrode section in each section of said insulator, said electrode sections having their ends spaced apart and located within 105 the cavities formed within the insulator.

In witness whereof, I subscribe my signature.

WILLIAM H. PLUNKETT.
